DROPPABLE CONTAINER

Charles P. Bender, Wabash, Ind., assignor to The General Tire and Rubber Company, Akron, Ohio, a corporation of Ohio

Application December 21, 1953, Serial No. 399,212

9 Claims. (Cl. 150---.5)

This present invention relates to a rubber drop tank which is filled with liquid or freely flowing fine particles and dropped from aircraft to ground receivers. It particularly relates to a rubber drop tank that is provided with a stabilizing flap to slow down and control its free-falling aerodynamic characteristics.

In the copending application of Paul O. Pfeiffer, Serial No. 262,116 filed December 17, 1951 and assigned to the same assignee as the subject invention, the process of filling rubber drop tanks with fluid or freely flowing fine particles and dropping them from aircraft to ground receivers is described. In accordance with this process, a rubber drop tank can be filled with a fluid such as gasoline and dropped to the ground from heights of around two hundred feet to one thousand feet or more.

The object of this invention is to provide a container for use in accordance with this process with superior aerodynamic characteristics and particularly a container that falls flat and right side up.

Other objects and advantages will become apparent from the following detailed description and the accompanying drawings illustrating this invention in which like numerals relate to like parts.

Figure 1 is a top plan view on a reduced scale of a droppable container constructed in accordance with this invention;

Fig. 2 is a cross-sectional view taken along line 2—2 of Fig. 1;

Fig. 3 is a fragmentary cross-sectional view taken along line 3—3 of Fig. 1 and on a larger scale showing the stabilizing flap of this invention;

Fig. 4 is a front elevational view showing the droppable container of Figs. 1 to 3 filled with liquid and showing in dot-dash lines how the slits in the stabilizing flap may be used as handles;

Fig. 5 is an enlarged fragmentary cross-sectional view taken along line 5—5 of Fig. 1 showing the closure means and filling handles for the container;

Fig. 6 is a fragmentary circular cross-sectional view taken along arc 6—6 of Fig. 1 indicating by dot-dash lines the method of attaching the filling handle to the container;

Fig. 7 is a front vertical cross-sectional view on a reduced scale showing a modified form of container constructed in accordance with this invention; and

Fig. 8 is a front elevation showing the approximate free-falling shape of the container of Fig. 7 when it is filled with liquid.

Containers constructed in accordance with this invention are filled with flowable materials such as gasoline, water, dry powders, or freely flowing fine particles such as sugar, salt, flour, and the like, and then dropped from an aircraft to the ground. The container lands upon the ground, expands horizontally to absorb the impact forces and then assumes its normal supported shape. Receivers on the ground collect the containers and empty them. It is contemplated that this process may be used in both

2

military and civilian work to supply persons behind enemy positions or in isolated locations.

The container is a relatively thin-walled, hollow body with filling means such as a plug generally in the center of the top portion. In the filled condition and resting on a horizontal support, the horizontal width is preferably at least five times the height and the shape of the container is generally spheroidal or ellipsoidal with the bottom portion of blunter profile than the top portion.

It should be oblate or depressed at the vertical poles. Thus the preferable shape of the container when filled and resting on a horizontal support is generally that of an oblate ellipsoid of revolution. Other shapes such as a pear shape or the like are also contemplated by this invention. The container shape should also be rounded and curving and have no sharp corners or stress concentration points and should preferably be symmetrical about its vertical axis.

The containers themselves are subject to extreme forces and must be constructed in accordance with definite limitations. In the first place, it is assumed that in the great majority of drops, the containers will reach their maximum or terminal velocity as they fall to and before reaching the ground so that they will normally strike the ground at their terminal velocity. To minimize the impact forces, therefore, I design my container to have a minimum terminal velocity and to have as much air resistance as can be incorporated therein without being unduly complex, costly, or cumbersome. I try to design the containers with terminal velocities below 300 feet/sec. and preferably around 100 feet/sec. or below.

The container is shaped so that spinning and whirling in the air is minimized and so that it will not otherwise fall in an erratic fashion. I have found that a skirt or flap around the maximum diameter of the container greatly assists in overcoming spinning and whirling during free fall.

One form of container or bag constructed in accordance with the subject invention is illustrated in Figs. 1—6. This container 1 comprises a circular top sheet or disc 2 and bottom sheet or disc 3 vulcanized together at lapped-over, seam portion 4. As shown in Fig. 3, the edge 7 of sheet 3 laps over the edge 6 of sheet 2 and they are vulcanized or cemented together at seam portion 4. The inner side of each sheet 2 and 3 may have a thin layer of aromatic resistant rubber-like material such as HYCAR or THIOKAL or the like so that gasoline can be transported therein without injury to the bag walls. The inner lining should be more flexible than the bag walls proper so that the lining does not absorb shock forces or become separated from the walls. It is contemplated that an outsized, loose lining of cellophane or polyvinylchloride sheet or the like could be inserted within the bag to protect special goods such as food products. A reinforcing disc 8 is preferably vulcanized to the central portion of the bottom sheet to reinforce and strengthen it.

The means for filling the container comprises a plug 9 which is screwed into a socket or flange 11. Around the top of the socket is a washer or gasket 12 to prevent leakage. The socket is built into the top portion of the bag with top and bottom circular rubber pieces 13 and 14 respectively as shown in Fig. 5. The plug is provided with a central depression 16 provided with ears 17 so that a tool or bar can be inserted into the depression to open the plug. Both the plug and socket are preferably made of a polyester resin reinforced with glass fibers.

The unfilled container is preferably provided with a circumferential hump portion 10 in sheet 2 around the top of the container adjacent the filler means as shown in Fig. 2. This portion extends completely around the top of the container. It provides extra stretchable material for the top portion of the container so that it can stretch

evenly with the bottom portion, or in other words, so that the top and bottom portions of the container have approximately the same amount of stretchable material. This is preferable because the flange around the plug is unstretchable and reduces the effective stretch of the top portion of this container. When the container is filled, the hump is preferably substantially eliminated.

In order to facilitate handling the container and particularly in order to facilitate filling the container, a rubber ring member 18 is vulcanized to the container to form handle portions 19 and 21 (Fig. 1). The ring member preferably has a fabric facing 22 on both sides and comprises two rings of rubber 23 and 24. As shown in Fig. 6, the bottom rubber ring 24 is split, folded back and vulcanized to the container and the exposed portion of the top ring is also vulcanized to the container. The remainder of the ring forms right and left handle portions 19 and 21 previously noted.

I also provide a stabilizing skirt or circumferential flap 26 around the central circumference of the container and extending appreciably beyond it to give the container aerodynamic stability and to decrease its terminal velocity. This flap 26 is generally attached or vulcanized to the container at or near the maximum circumference of the container or near the juncture or seam portion 4 of the discs 2 and 3. It is preferably made from a ring of rubber-like material which is vulcanized or cemented to the container as shown in Fig. 3. It should have a width or diameter so as to extend beyond the margin of the container wall in substantially a horizontal direction of from around one eighth to one half the radius of the bottom portion of the container as assembled, or, in other words, from seam 4 to the vertical axis of the container. Thus for a bottom sheet radius of approximately 12 inches, the flap should preferably extend 3 inches beyond the seam. It should be attached to the container body in the vicinity of the maximum diameter and should extend an appreciable distance in a horizontal direction beyond the side of the body or beyond maximum circumference of the container body. In Fig. 3 it is shown vulcanized to the container at seam portion 4.

Opposite sides of the skirt are provided with handle portions 27 and 28 consisting of fabric pieces 29 and 31 vulcanized over slots 32 in the skirt. The fabric over the slots is then slit as at 33 to form handles or hand grips suitable for lifting and handling the container as is illustrated in Fig. 4.

The container 1 when filled and resting on a horizontal support as in Fig. 4 assumes substantially the shape of an oblate ellipsoid of revolution substantially symmetrical about a vertical axis in which the discs 2 and 3 are bowed or bulged outwardly. When the container is collapsed, the discs are substantially flatwise against one another and the upper disc 2 has a slightly greater diameter than the other disc 3.

Fig. 7 shows a modified form of container constructed in accordance with my invention. Container 35 comprises a circular top sheet or disc 36 and a circular bottom sheet 37 of smaller diameter than the top sheet joined to the top sheet along seam 38. If desired, seam 38 may be reinforced as with stitching or rivets.

A portion of the top sheet extends beyond seam 38 to form flap portion 39 functioning similarly to flap 26 on container 1. It should extend beyond seam 38 in substantially a horizontal direction a distance of from one-eighth up to one-half the radius of bottom sheet 37 and preferably a distance of around one-quarter of this distance.

The plug 40, socket 41, and filling handle ring 42 form a closure and filling means for the container similar to that of container 1. Likewise, flap portion 39 is provided with cloth reinforced handle portions 43 and 44 similar to those of container 1.

It is, of course, desirable to have the filled container

fall and land in its normal, upright position so as not to injure the valve or plug for emptying and filling the container, to minimize terminal velocity, and to minimize the landing shock and stresses on the container.

5 In order to aid in accomplishing this result, I shape that portion of the container opposite from the filling valve and near the maximum horizontal diameter so that the container when filled and freely falling provides increasing air resistance as it is tilted earthward from the horizontal. That is, the lower part of the container is shaped so that, when the axis of the container is tipped from the vertical, the air resistance of the higher portion of the container will decrease and the air resistance of the lower portion will increase. A self-righting effect is thus 10 obtained similar to that caused by the dihedral angle in airplane wings, the stabilizing skirt greatly assisting in this action. The outer portions of the cross-sectional curve of my container may be made to be flat, concave, or only slightly convex to obtain the desired self-righting effect.

The container of Figs. 7 and 8 is provided with excellent stabilizing means, Fig. 8 showing the approximate shape of this container when it is filled and freely falling so that the action of the stabilizing flap 39 is apparent. It will be noted from Fig. 8 that the bottom sheet 37 has a convex outer surface of revolution that decreases in curvature and extends generally in a radial direction adjacent its margin so that, in cross section, there is a sharp interior angle formed by the top sheet 36 and the marginal portion of the bottom sheet 37. In other words, the radially outer portion of the bottom sheet 37 is generally tangent to the top sheet 36 and its flap portion 39.

The material used in making my container should be 35 tough, abrasion resistant, and flexible. Suitable materials are natural and synthetic rubbers and rubber-like materials. The required physical characteristics of the material must be adapted to the goods transported in the container taking into account their specific gravity, solvent action, compatibility, and sanitation requirements.

A suitable material must satisfy a combination of several requirements in as even a balance as possible. The material has to be quite flexible in order to give and distort on landing and thereby absorb and dissipate the landing forces. At the same time, it should have sufficient modulus so that a filled container retains shape on the ground and the walls do not collapse. The bag should 45 preferably be sufficiently rigid in the filled state so that it can be readily stacked and moved about. It should also have sufficient modulus so that the shape of the container during free fall is one providing maximum air resistance and is not distorted to a streamline teardrop shape. At the same time, bags constructed in accordance with this invention should have no unstretchable continuous reinforcing material in the walls because this unduly limits the wall elongation and flexibility. The material finally should have toughness and abrasion resistance to stand handling and resist ground hazards such as trees, rocks, and stubble.

The material for this container can be any high abrasion 60 resistant, nervy, flexible rubber or rubber-like material such as natural rubber, butadiene-styrene rubbers, butadiene-acrylonitrile rubbers, isobutylene rubbers, and other rubbery elastomeric materials. Minimum tensile strength should be 1500 p. s. i. and preferably over 2500 p. s. i. and minimum elongation at break should be around 400 percent. The bag wall section, regardless of thickness, ought to have a tensile strength or pull of 2000 p. s. i. or above at 500 percent elongation. Thus, if a low modulus material is used, the wall should be relatively thick and conversely, if a high modulus material is used, the wall should be relatively thin. A suitable container has a wall pull or tensile strength of 4000 p. s. i. at 500 percent elongation. The material should be compounded to provide high abrasion resistance and toughness. A rubber stock should pref-

erably have 25 parts or more of a reinforcing carbon black or equivalent to provide toughness, hardness, abrasion resistance, and resistance to cutting. High quality tire tread stock satisfying the above noted physical characteristics is suitable for use in my containers.

It is contemplated that bags constructed in accordance with the subject invention will have a capacity of five, ten, twenty-five, or even more gallons. Using the same stock, the bag wall thickness should be increased when the bag is designed for heavy liquids such as water instead of lighter liquids such as gasoline.

It is understood that the invention disclosed can be constructed in a number of ways within the scope of the appended claims and that it is not to be limited to the embodiments herein described.

Having thus described my invention, what I claim is:

1. A droppable free-falling container for aerial delivery which comprises walls formed of two substantially circular rubber discs of substantially the same diameter joined at their peripheries, said discs having a minimum tensile strength of 2000 p. s. i. at 500 percent elongation and each being substantially flat in the unstressed condition and being disposed flatwise against one another when the container is collapsed, a stabilizing flap comprising a ring of rubber-like material joined to said container adjacent the juncture of the two discs and extending in a substantially horizontal direction appreciably beyond the side of the container, said container when at rest on a flat supporting surface and filled with liquid assuming substantially the shape of an oblate ellipsoid substantially symmetrical about a vertical axis with the horizontal width at least five times the height in which the two discs are bowed outwardly and one disc includes a substantially circular flattened area of less diameter than the disc which is in contact with such supporting surface.

2. A container for aerial delivery of a freely-flowing material to the ground from an air vehicle traveling at substantial altitude comprising: an extensible elastic rubber bag with a volumetric capacity of several gallons having thin circular top and bottom walls joined at their peripheries which walls may be extended several times their normal diameter, the rubber of said walls containing at least about 25 parts of a reinforcing carbon black and being capable of withstanding a tension of at least about 2000 pounds per square inch when elongated five hundred percent, said bag when completely filled with said material and resting on a flat horizontal surface having an axial height not substantially greater than about one-fifth its diameter and when falling freely having a shape generally corresponding to that of an oblate ellipsoid of revolution with a normally upright axis, and means for stabilizing said bag during its free fall so that said axis remains upright during the fall to minimize the terminal velocity and is upright when the bag strikes the ground, said stabilizing means comprising a circumferential flap of rubber-like material united with and extending radially outwardly from the margin of said bag and having an average width that is around one-eighth to one-half the radius of the lower portion of the bag.

3. A container for aerial delivery of water, gasoline, or other liquids to the ground from an air vehicle traveling at substantial altitude comprising: an extensible elastic

rubber bag with a volumetric capacity of at least about five gallons having thin circular top and bottom walls, joined at their peripheries which are substantially free of inextensible reinforcement and may be stretched several times their normal diameter, the rubber of said walls being capable of withstanding a tension of at least about 2000 pounds per square inch when elongated 500 percent, said bag when completely filled with said material and resting on a flat horizontal surface having an axial height not substantially greater than about one-fifth its diameter and when falling freely having a shape generally corresponding to that of an oblate ellipsoid of revolution with a normally upright axis, and a stabilizing flap comprising a ring of rubber-like material united with said container adjacent the juncture of the top and bottom walls and extending radially outwardly from said juncture, said flap maintaining the axis of the bag in an upright position during the free fall and increasing the air resistance of the container so that the bag has a terminal velocity less than 300 feet per second.

4. A container as defined in claim 2 wherein a reinforcing disc is bonded to the interior face of said bottom wall at the central portion thereof and wherein means is provided at the center of said top wall for insertion and removal of liquid.

5. A container as defined in claim 3 wherein said flap is integral with one of said walls.

6. A container according to claim 3 wherein the bottom wall decreases in curvature adjacent its margin.

7. A container as defined in claim 3 wherein the marginal portion of the bottom wall extends generally in the same direction as the flap.

8. A container as defined in claim 7 wherein said top wall and said flap are integrally united as a single sheet of elastic rubber, said bottom wall having a radially outwardly extending marginal portion parallel to and bonded to said sheet throughout its circumference.

9. A container for aerial delivery of water, gasoline, or other liquids to the ground from an air vehicle traveling at substantial altitude comprising: an extensible bag of elastic material having thin circular top and bottom walls which may be stretched several times their normal diameters, the bottom wall being joined at its periphery to the top wall, and means for stabilizing the bag during its free fall including a ring of elastic material united with said bag adjacent the juncture of the top and bottom walls and extending radially outwardly from said juncture to provide a stabilizing flap, said means for stabilizing the bag maintaining the axis of the bag in an upright position during the free fall and increasing the air resistance of the container so that the bag has a terminal velocity not substantially in excess of about one hundred feet per second.
